UNITED STATES PATENT OFFICE.

EBENEZER W. RIDER, OF RACINE, WISCONSIN.

FEED-CUTTER.

SPECIFICATION forming part of Letters Patent No. 378,112, dated February 21, 1888.

Application filed December 27, 1886. Serial No. 222,635. (No model.)

To all whom it may concern:

Be it known that I, EBENEZER W. RIDER, of Racine, in the county of Racine, and in the State of Wisconsin, have invented certain new and useful Improvements in Feed-Cutters; and I do hereby declare that the following is a full, clear, and exact description thereof.

My invention relates to feed-cutters; and it consists in certain peculiarities of construction and combination of parts, to be hereinafter described with reference to the accompanying drawings and subsequently claimed.

In the drawings, Figure 1 represents a front elevation of my invention; Fig. 2, a side elevation; Fig. 3, a similar view with the driving-gear removed, and Fig. 4 a detail view of a pawl-and-ratchet mechanism for actuating the feed-rolls.

Referring by letter to the drawings, A represents the feed-box of my machine, mounted in a suitable frame, said box being provided at its front end with a shear-plate, B, and secured to the frame adjacent to this plate is a knife-guard, C. Journaled in suitable bearings so as to operate within the box A are feed-rolls D D', of the ordinary construction and adjustment. Fast on the journals a a' of the feed-rolls D D', at the drive side of the machine, are ratchet-wheels E E', and loose on these journals are arms F F', the latter having pivotally connected thereto pivoted spring-actuated pawls G G', that engage said ratchet-wheels.

In Fig. 4 I have shown a detail view of the pawl-and-ratchet mechanism, and in this instance I employ a spring, b, to keep the pawl G in engagement with the arm F.

If found desirable, the pawl G' may be weighted, as shown at c, Figs. 2 and 3.

To the arms F F', I pivotally connect the forward ends of links H H', that have their rear ends similarly connected to the vertical ears d of a rack-plate, I, the latter being operatively arranged in guides e, suitably secured to the box A.

The forward end of the rack-plate I is turned out at right angles to form an ear, f, and this ear has a perforation that serves as a guide for a rod, J, connected with a crank-arm, K, on the inner end of a short shaft, K', operative in a suitable bearing, g, secured to an extension of a transverse brace, L, that is in turn fastened

to the under side of the box A, said short shaft being provided with a bevel-pinion, M, keyed thereto at its outer end. The rod J is provided with a collar, h, and between this collar and the ear f of the rack-plate I is arranged a spiral spring, N, the tension of the latter being regulated by a thumb-nut, i, on the forward end of said rod.

Pivottally connected to the adjacent side of the box A is a dog, O, that serves to engage the rack-plate I at such times as it may be desirable to stop the feed of the rolls D D'.

In order to vary the feed of the rolls D D', the crank-arm K is provided with a series of perforations, j, and the throw of the rod J is consequently lengthened or shortened, according to its engagement with said perforations.

Meshing with the bevel-pinion M is a similar pinion, P, on the adjacent end of a crank-shaft, Q, that has its bearing k k', respectively, secured to the extension of the cross-brace L and a standard, L', at the front of the frame. To the crank-portion Q' of the shaft Q is loosely connected one end of a knife, R, that comes across the mouth of the feed-box A, the opposite end of this knife being also loosely connected to a stud, m, on the lower terminus of a curved lever-arm, S, pivotally secured to a front standard, T', of the supporting-frame and projected over to nearly or quite the transverse center of said box.

The crank-shaft Q has keyed thereto a fly-wheel, U, and by a suitable construction and arrangement of gearing any desired speed may be given said shaft. In this instance I show a bevel-pinion, V, fast on the shaft Q and arranged to mesh with a bevel gear-wheel, W, journaled in a bearing, X, secured to the extension of the cross-brace L, said wheel being twice the diameter of the intermeshing pinion and having a crank, Y, fast on its journal. If found desirable, the speed-gear may be omitted and the crank Y applied to the fly-wheel U.

A spring-arm, Z, has one end thereof rigidly secured to the under side of the brace-piece L and its other end brought over upon a transverse bar, Z', to which latter are adjustably connected straps n, that hold the upper feed-roll, D, down to its work.

Supposing the knife R to be in the position

shown by Fig. 1, when the crank-shaft Q is operated this knife will be drawn thereby toward the operator, while at the same time the lever-arm S operates to drive said knife in the same direction, whereby a double power is exerted to produce an easy, sliding, and shear cut in a direction away from said operator. While the machine is running that end of the knife R nearest the operator describes a circle, o, as shown by dotted lines, Fig. 1, the other end of said knife traveling on an arc, p, of a circle having a larger diameter than the one o, and also illustrated by dotted lines in the same figure. The knife R begins to cut at that side 15 of the box nearest the operator and gradually performs its function as the opposite side of this box is approached, the inclination of this knife being diminished as the work proceeds until at the time its edge has entirely passed 20 the shear-plate B said knife will be nearly or quite horizontal.

In Fig. 1 is shown by dotted lines the knife in various stages of its descent, and by this illustration it will be noticed that said knife 25 does not come at any one time on the whole mass that may protrude from the mouth of the feed-box. The pinion M, meshing with the pinion P on the crank-shaft, imparts motion to the crank-arm K, and this latter part 30 in turn imparts motion to the rod J, that has a loose bearing in the ear f of the rack-plate I. When the dog O is clear of the rack-plate I, the latter is actuated by the rod J, and, being linked to the arms F F', causes the pawl- 35 and-ratchet mechanism, previously described, to partially rotate the feed-rolls D D' when the knife R is on its return after completing a cut, thereby bringing more material from the box A into the path of said knife, the length of 40 feed being regulated by the throw of the rod above described.

When it is desirable to stop the revolution of the feed-rolls, the dog O is dropped, and the rack-plate I is thereby held stationary, the 45 rod J having its play through the perforation in the ear f of said plate.

Having thus fully described my invention, what I claim as new, and desire to secure by Letters Patent, is—

50 1. In a feed-cutter, the combination of a box mounted in a frame, feed-rolls operatively arranged in the box and having their journals

at one end provided with ratchet-wheels, arms loosely arranged on said journals and carrying pawls to engage the ratchet-wheels, a plate 55 loosely connected to the adjacent side of said box, links uniting the pawl-arms and loose plate, a pinion having its journal provided with a crank-arm, a rod uniting the loose plate with the crank-arm, and a drive-shaft having 60 a pinion arranged to mesh with the one above specified, substantially as and for the purpose set forth.

2. In a feed-cutter, the combination of a box mounted in a frame, feed-rolls operatively 65 arranged in the box and having their journals at one end provided with ratchet-wheels, arms loosely arranged on said journals and carrying pawls to engage the ratchet-wheels, a loose 70 rack-plate operatively connected to the adjacent side of said box and united by links with the pawl-arms, a pivoted dog arranged to be brought into engagement with the rack-plate, a pinion having its journal provided with a crank-arm, a rod having a loose bearing in an 75 ear of said rack-plate and connected with the crank-arm, a spring arranged on the rod, and a drive-shaft having a pinion arranged to mesh with the one above specified, substantially as and for the purpose set forth. 80

3. In a feed-cutter, the combination of a suitable frame, a box mounted in the frame, feed-rolls arranged in the box, a transverse 85 knife, a crank-shaft loosely connected to one end of the knife, a lever-arm likewise connected to the other end of said knife, ratchet-wheels fast on the journals at one end of the feed-rolls, suitable arms loose on said journals and provided with pawls to engage the ratchet-wheels, a sliding plate connected to said box, 90 links uniting the pawl-arms and plate, a crank-arm, a rod uniting the sliding plate and crank-arm, and a pinion-gear connecting said crank-arm and crank-shaft, substantially as and for the purpose set forth. 95

In testimony that I claim the foregoing I have hereunto set my hand, at Racine, in the county of Racine and State of Wisconsin, in the presence of two witnesses.

EBENEZER W. RIDER.
